Inventor:

Joseph P. Glaser,
Bacon & Milans Attorney:

UNITED STATES PATENT OFFICE.

JOSEPH P. GLASER, OF DETROIT, MICHIGAN, ASSIGNOR TO CHAMBERLIN METAL WEATHER STRIP COMPANY, OF DETROIT, MICHIGAN.

WEATHER-STRIP.

1,379,910.

Specification of Letters Patent. Patented May 31, 1921.

Application filed September 27, 1917. Serial No. 193,521.

To all whom it may concern:

Be it known that I, JOSEPH P. GLASER, citizen of the United States, residing at 109 Third Ave., Detroit, in the county of 5 Wayne and State of Michigan, have invented certain new and useful Improvements in Weather-Strips, of which the following is a specification, reference being had therein to the accompanying drawing.

10 The present invention relates to improvements in weather strips and more especially has to do with that type of devices particularly adapted for casement windows and the like, in which a metal strip element applied 15 to the sill of the window frame is employed to coöperate with a part or metal strip element on the lower rail of the sash.

The primary object of the invention is to 20 provide an improved sill strip capable of being readily adjusted to suit sill and sash rail structures of different widths, to provide an improved adjustable sill strip of this nature that will be simple in construction, strong and durable, and that can be 25 manufactured very cheaply.

The invention, with other objects and advantages thereof and the particular construction, combination and arrangement of parts comprising the same will be understood 30 from the following detailed description considered in connection with the accompanying drawings forming part hereof and wherein is illustrated a preferred embodiment of the invention and one modification thereof.

In the drawings:

Figure 1 is a vertical section of a casement window equipped with a weather strip constructed in accordance with the present 40 invention, the sash being shown in closed position.

Fig. 2 is a detailed perspective view of the sill strip.

The invention comprehends a sill strip 45 made up of two metal members, each of the members having an upstanding part for co-operation with a part on the sash, and with an outstanding portion, said members adjustably interfitting together with the upstanding parts separated from each other 50 and the outstanding portions overlapping each other and forming a channel therebetween.

The particular embodiment of the invention 55 illustrated in Figs. 1 and 2 of the

drawings comprises a sill strip composed of two members A—B formed from strips of flexible sheet metal, such as sheet zinc, copper and the like. The member A has two upstanding flanges $a-a'$ at opposite sides thereof with an intermediate outstanding connecting portion a^3 , said member being formed by turning up opposite side marginal portions of the strip. In forming the member B, the strip of metal is doubled 60 back upon itself intermediate its side marginal portions to provide a double wall upstanding flange b , and the outstanding portions $b'-b^2$ at opposite sides of the flange b , the latter flange b at its upper 70 portion being bent at an angle to provide the offset portion b^3 , the opposite walls of the flange b , below the portion b^3 , being separated to provide a space b^4 therebetween. The members A—B are assembled 75 in interfitting relation, as shown in Fig. 1 of the drawings, with the outstanding flange or portion b' of the member B fitting over the outstanding flange a^3 of the member A, and with the upstanding flange a of the 80 member A extending upwardly within the space b^4 between the opposite walls of the flange b , the space b^4 being of sufficient width to permit the lateral shifting of the flange a within the said space in the lateral adjustment of the members A—B relative to 85 each other to vary the distance between the upstanding flanges $a-b$ of the respective members. The interfitting members are secured together in adjusted position upon 90 the upper face of the sill C of the window frame by a row of tacks or similar fastening members c extending through the overlapping outstanding portions a^3-b' of the 95 respective members.

Secured upon the lower face of the lower rail I of the window sash within the rabbet I' for coöperation with the sill strip is a metal strip element K, said strip element K having at one side thereof a substantially 100 hook-shaped resilient pocket k.

When the window sash is in its closed position, that shown in Fig. 1 of the drawings, the outwardly bent upper portion b^3 of the flange b fits tightly within the resilient 105 pocket k of the sash strip K, and the upstanding flange a of the member A of the strip abuts tightly against a part on the lower portion of the sash rail I. In this special instance, the sash rail is provided 110

with a rabbet *l* in which the upper end of the flange *a* fits with its inner face tight against the inner wall *l'* of the rabbet.

In order to permit the escape of any moisture that may enter the channel between the upstanding flanges *a*—*b*, small openings *d* are provided in the lower portion of the flange *a*.

It will be noted that the invention provides for a very efficient weather proof fitting, the sill strip is of a strong, durable nature, simple in construction, and can be economically manufactured from stock materials. The adjustable feature of the sill strip is of practical importance facilitating installation and making it possible to employ one size of strip to equip sill and sash parts of different widths.

I desire it to be understood that minor changes and variations in the particular construction as illustrated in the drawings as will appeal to those skilled in the art and within the scope of the appended claims may be made without departing from the spirit of the invention.

What I claim is:

1. A sill strip for casement windows and the like comprising a metal member having two spaced upwardly extending flanges and an intermediate connecting portion, and an associated member adjustably interfitting with the other member formed of an independent strip of metal folded upon itself to provide a double walled upstanding flange

and a horizontally extending base flange at 35 one side thereof, the opposite walls of the double walled flange being separated from each other to provide a space therebetween, one of the upwardly extending flanges of the other member being disposed within and 40 adapted to be positioned at different points within said space in the adjustment of the members relatively to each other.

2. A sill strip for casement windows and the like, comprising a metal member having 45 two spaced upwardly extending flanges, and an intermediate connecting portion, and an associated member adjustably interfitting with the other member and formed of an independent strip of metal folded upon itself 50 to provide a double wall upstanding flange, the upper portion of the flange being bent outwardly at an angle, and the opposite side walls of the flange below said outwardly bent upper portion being separated from each 55 other to provide a space therebetween to receive one of the flanges of the other member and permit of the positioning of the same at different points within said space, one of the flanges of the upper member being disposed 60 within said space between the walls of the flanges of the other member.

In testimony whereof I hereunto affix my signature in the presence of two witnesses.

JOSEPH P. GLASER.
